STOP MEANS FOR LOOMS

Floribert H. Tetreau, Uxbridge, Mass.

Application April 27, 1943, Serial No. 484,747

2 Claims. (Cl. 139—337)

This invention relates to new and useful improvements in stops for looms, and more particularly for stopping of a loom in the event any one or more of the usual harness straps breaks.

The principal object of the present invention is to provide a stop for looms which will instantly stop a loom in the event any one of the harness straps breaks, thus obviating the time consuming occupation that is ordinarily necessary when a loom has been functioning for some time with a broken strap, the cloth obviously being then defective to the extent that one or more threads must be picked out of the cloth.

Another important object of the invention is to provide a stop of this character which is substantially foolproof and positive acting in all respects.

Other objects and advantages of the inventions will become apparent to the reader of the following description.

In the drawings:

Figure 1 presents a portion of a loom showing a harness frame and its attached straps in conjunction with the present invention.

Figure 2 is a sectional view showing a bank of harness frames, their straps and how they are associated with the present invention.

Figure 3 is a detailed sectional view showing the switch means.

Figure 4 is a perspective view of the bridging contactor.

Referring to the drawings wherein like numerals designate like parts, it can be seen that numeral 5 denotes a loom frame and certain other parts of a loom are shown, principally a bank of loom harness frames 6 which are supported by upper and lower straps 7, 8, respectively. Very frequently one or more of thees straps on one or more frames 6 breaks, resulting in a defective weave.

In carrying out the present invention, a contact bar 9, such as is found on some types of looms, is employed with a special type of contactor generally referred to by numeral 10. The contact bar 9 is used on some looms in conjunction with complementary switch means in various stop motion activities. This type of bar 9 consists of an elongated conductor element, or shell, 11 open at one side, but having inturned side edge flanges, as at 12, 12, and this is lined with a sheet of insulation 13 so as to cover the closed side and also the edge flanges 12. The side portions of an elongated conductor strip 14 are interfitted with the side edges of said sheet of insulation 13, the longitudinal intermediate por-

tion of the conductor strip 14 being bulged as at a, toward the open side of the shell and exposed therethrough, while a longitudinally extending rib b is provided on the outside of the closed 5 side of the shell 11, the bulge a and rib b being adapted to be engaged by opposed protuberances, or contacts, 15, 15 on the inner sides of the legs 16, 16 of a bridging member 17 which is of U shape and which has an upstanding stem 18 passing through a bracket arm 19.

The upper end of the stem 18 has a nut 20 and a coiled compression spring 21 is interposed between the bracket arm 19 and the nut 20.

A cable or other lineal element 22 extends from 15 a stud or other anchoring element 23 on one leg 16, downwardly and under a pulley 24, from where it extends horizontally under the lower straps 8 to connect to a bracket 25 at the distal end of the frame 5.

It can now be seen that the spring 21 is very 20 delicate, just barely strong enough to maintain the bridging contactor 17 in elevated position as shown in Figure 3.

Should one or more of the harness frame straps 25, 8 break, this would result in a slackening of the corresponding lower strap which would fall onto the cable or lineal element 22, causing a slight depression thereof, just sufficient enough to draw down the bridging member 17 so that 30 the protuberances or contacts 15, 15 can engage the bulge a, and ribs b of the conductor element 11, 14, thus closing a circuit with a suitable electrical stop mechanism (not shown).

While the foregoing specification sets forth the 35 invention in specific terms, it is to be understood that numerous changes in the shape, size, and materials may be resorted to without departing from the spirit and scope of the invention as claimed hereinafter.

Having described the invention, what is claimed 40 as new is:

1. In a loom structure, harness frame provided with harness straps, an elongated flexible element anchored at one end and provided at its 45 opposite end with stop motion operating means, said elongated flexible element being disposed in a position underlying certain of the straps so that in the event one of the straps breaks, the weight of the strap imposed on the elongated element will effect operation of the stop mechanism, said stop motion operating means comprising a pair of contact elements, a member bridging the contact elements, a spring support for the bridging member, said elongated flexible 50 element being attached to the bridging member,

and a conductor element provided with outwardly disposed bulges against which the contacts can engage, said bridging member being of U shape to straddle the conductor elements.

2. In a loom structure, harness frame provided with harness straps, an elongated flexible element anchored at one end and provided at its opposite end with stop motion operating means, said elongated flexible element being disposed in a position underlying certain of the straps so that in the event one of the straps breaks the weight of the strap imposed on the elongated element will effect operation of the stop mechanism, said stop motion operating means com-

prising a pair of contact elements, a member bridging the contact elements, a spring support for bridging the contact, said elongated flexible element being attached to the bridging contact, a conductor element provided with outwardly disposed bulges against which the contact elements can engage, said bridging member being of U shape to straddle the conductor element, said spring being barely strong enough to support the bridging member away from the conductor element and weak enough to yield to the weight of a single harness strap.
